[57] CLAIM

The ornamental design for an eyewear, as shown and described.

DESCRIPTION

FIG. 1 is a front elevational view of an eyewear showing my new design;

FIG. 2 is a front perspective view thereof;

FIG. 3 is a rear elevational view thereof;

FIG. 4 is a top plan view thereof;

FIG. 5 is a side elevational view thereof;

FIG. 6 is a bottom plan view thereof;

FIG. 7 is a front elevational view of a second embodiment of my new design;

FIG. 8 is a front perspective view of FIG. 7;

FIG. 9 is a rear elevational view of FIG. 7;

FIG. 10 is a top plan view of FIG. 7;

FIG. 11 is a side elevational view of FIG. 7; and,

FIG. 12 is a bottom plan view of FIG. 7.

The dashed lines appearing in FIGS. 7-12 are for environmental purposes only and form no part of the claimed design.
